Felix G. White, 2815 Riverside Drive, Dayton 5, Ohio

Filed May 25, 1961, Ser. No. 65,340

Term of patent 14 years

(Cl. D4—3)

I claim:

The ornamental design for a soap dish, as shown and described.
